UNITED STATES PATENT OFFICE.

AUGUST J. RICK, OF ST. LOUIS, MISSOURI, AND JOHN FLIEDNER, OF FLUSHING, NEW YORK, ASSIGNORS TO AMERICAN MANUFACTURING COMPANY, OF BROOKLYN, NEW YORK, A CORPORATION OF MASSACHUSETTS.

DRAWING FRAME.

Application filed April 6, 1926. Serial No. 100,008.

Our invention relates to drawing frame particularly machines of that character used for drawing hemp, and consists in a novel form of feeder and an automatic stop therefor.

Figure 1 is a side elevation illustrating the automatic stop;

Figure 2 shows the stop and electric circuits therefor;

10 Figure 3 shows an elevation of the receiving cans and shift mechanism therefor;

Figure 4 is a plan view of Figure 3;

Figures 5, 6, and 7 show right and left side views of the feeder and details of the 15 electric contact;

Figure 8 is a plan view of the feeder;

Figures 9, 10, and 11 show details of the feeding rolls; and

20 Figure 12 is a plan view of a modified form of feeder.

In Figure 1, we have shown at A the drawing machine in outline, there being no novelty in that machine itself claimed herein. At the left we show at B one end of the novel 25 form of feeder we have devised for bringing the material to and delivering it into the machine. Above the machine and mounted on a bracket C² is the box C containing the electro-magnets and battery of the automatic stop mechanism, the same being shown 30 more fully in Figure 2.

The feeder aforesaid has for its supporting frame a series of parallel beams B³ (Figs. 5, 6, 8, and 9), each mounted at one end on a bracket B² projecting from the left side of the machine as shown in Figure 1. These beams are shown in side view in Figures 5 and 6, of which the former is taken from the right side of the feeder looking from its rear end towards the carding machine, and the latter from the opposite left end. The beams are also shown in cross-section in Figure 9. These beams form the bearing support for three transverse fluted or grooved feed rolls D, D² and D³ (Figs. 8 and 9), which extend clear across the frame. A cross-section of feed roll D³ is shown in Figure 10, from which it appears that the ribs between the succeeding grooves are square-edged and the grooves themselves square-edged at the bottom. This gives the rolls a better bite on the slivers of hemp which they feed forward as they rotate. The several bearings for the rolls, of which there are three shown, one at

each end and one in between, are all alike 55 and the description of one applies to all. This bearing (see Figure 10) comprises a bracket E mounted on the upper side of a beam 3, but insulated therefrom electrically by a block e. The bracket E is somewhat L-shaped and in its upper end is journaled the shaft of the roller by an insulating bushing e² (see Figure 9). By this means each roller is insulated from the rest of the machine, but is connected to form one terminal of an 60 electric circuit by means of a spring-pressed and insulated contact pin G that bears constantly against a washer g on the left hand end of each roller (see Figure 7). The first grooved roller D is rotated by means of a 65 sprocket chain b, driven by a shaft of the main machine, and an insulated sprocket wheel h on the shaft of the roller (see Figure 8). The second roller D² is driven from the first one D by means of a sprocket chain b² 70 and sprocket wheels h and h², while the third roller D³ is similarly driven from the second one D² by a sprocket chain b³ and sprocket wheels h⁴ and h⁵, all of the sprocket chains being insulated from the rollers. 75

The aforesaid brackets E also support a non-rotating shaft F parallel and closely adjacent to each of the rollers D, D² and D³ respectively. The shafts F are not insulated 80 from the brackets E. At each point along the 85 grooved rollers where a line of hemp is to be fed, a pair of curved yokes K, K are mounted on stationary shaft F and carry a short barrel pressure roll P. The roller P has a short shaft at each end resting by gravity in the bottom 90 of a notch formed in the upper end of each yoke K. The curve in yoke K allows it to encircle one-half of the grooved roller and bring the pressure roller P directly above it. The outer edge of the curved portion of each 95 yoke K is also flattened to a thin edge to form a converging channel for the hemp as it approaches the grooved roller. In operation a line or sliver of hemp of a width about equal to the length of a pressure roller P is drawn vertically upward from a pile adjacent to the machine and passes over one of the grooved rollers and beneath one of the pressure rollers P, which by its weight holds it against the grooved roller, which by its rotation feeds the 100 hemp along. Thus, referring to Figures 5 and 8, a sliver R³ near the left end of the figure is drawn up and passes over roller D³. 105

near the outer frame beam B^3 and then proceeds over rollers D^2 and D to the carding machine, being upheld, between D^2 and D , by a table S . Similarly a second sliver R^4 at a point near the intermediate beam B^3 is also drawn upward by the same roller D^3 and passed forward in like manner over rolls D^2 and D to the machine proper. A third sliver R^2 is drawn up by the intermediate roller D^2 and passes over that roller and roller D to the machine, while a fourth sliver R is drawn up by the roller D and after passing over it goes directly into the machine. There are four more slivers drawn up in like manner by the rolls between the intermediate beam B^3 and the upper or left hand beam B^4 , making eight slivers in all that are fed to the carding machine. These are recombined in the machine to make four carded slivers that are finally delivered from the machine into the four receiving cans, of which two are shown for illustration in Figure 4 marked respectively T and T^2 .

In Figure 12 a modified arrangement is shown wherein there are but two feed rollers, D and D^3 , the intermediate one, D^2 of Figure 8, being omitted. In this arrangement there are, in all, four slivers started initially by roller D^3 at different points along its length, and passed over roller D to the carding machine, while another four are started by roller D and passed directly therefrom to the machine. At each of the short barrel-shaped rollers P there is provided a scraper or cleaner N (see Figure 10) of rubber, which bears diagonally and yieldingly on the feed roller to keep the feeding edges of the roller ribs clear and at the same time preserve the electrical insulation of the roller.

The automatic stopping of the machine is dependent on the absence of the fed material between any pressure roll P and its feed roller whereby the two rolls, which form the opposite terminals of an electric circuit, come in contact and close that circuit. The closure of the circuit brings into action an electro-magnetic belt-shifter which throws the driving belt of the machine from the fast to the loose pulley and stops it. The stopping also occurs whenever the sliver becomes bunched on one edge or is otherwise so disarranged that the two rollers come in contact. For example, in Figure 9 the fed material is in its normal condition under the two rollers P , P at the right and the one roller P at the left. But of the remaining two rollers, the left hand one has no sliver under it, so that it rests on the feed roller, while the one at the right has been tilted up at one end by the bunching of the sliver along its left edge, thereby bringing the right hand end of roller P into contact with the feed roller. In either case the machine will be stopped.

The details of the stopping mechanism are shown in Figure 2. The fast pulley is marked

11, the loose pulley 10, and the belt 12. The shifter fork 13 is mounted on the end of a slide rod 14, which is normally pressed towards the right by a spring 17 to bring belt 12 on loose pulley 10. When rod 14 is moved to the left by hand to throw belt 12 on fast pulley 11, the rod is caught by a latch 16, which drops in notch 15 in the upper edge of the rod and is held against the pressure of spring 17. The circuit which is closed by the aforesaid contact of the pressure and feeding rollers may be traced from battery Z to the controlling rollers and thence by wire 40 to relay magnet Y back to the battery, switch 20 being closed and shunt-resistance 19 serving to adjust the strength of the magnet. The action of relay Y closes the circuit of the heavier latch-lifting magnet X which may be adjusted in strength by the switch 23 that either puts resistance in series with X or short-circuits said resistance. The local circuit for magnet X is from battery Z^2 to contacts 24 to X and then either through resistance 18 or the short circuit around it to the wire 42 and back to the battery the switch 21 being closed. A switch 22 is provided for stopping the machine by hand, the hand closure of the circuit by switch 22 having the same effect as the automatic closure thereof by the rolls.

The slivers are respectively delivered by the carder into a series of receivers T , T , etc., which are kept in oscillation as described in application for patent by John Fliedner, filed January 2, 1926, Serial No. 78,751. The mechanism for thus oscillating the receivers is indicated in Figures 3 and 4. Referring to those figures, the table T^2 on which receiver T rests carries a large gear wheel T^3 which is slowly rotated by a vertical shaft 50 through a train of reducing gears 51. The vertical shaft 50 is driven in periodically reversed directions by the bevel gears 52 and 53, which are periodically and alternately clutched to the horizontal shaft 54, which is driven constantly by bevel gears on shaft 55 which, in turn, is driven from the carder by a belt 56. The clutch is periodically shifted by a groove-wheel cam 57 on shaft 58 which is driven from shaft 54 by gearing 59. The clutch is marked 60 and its shift-lever 62 has a pin that rides in the groove of cam 57.

What we claim is:

1. A drawing machine feeder comprising rollers electrically insulated and normally separated by insulating carding material, fast and loose driving pulleys, and a shiftable belt thereon, a shifter fork mounted on a slide rod normally spring-pressed to bring the belt on the loose pulley, an electrically controlled latch for said rod, and an electro-magnet controlling said latch and contained in a circuit having its opposite terminals formed by the said rollers respectively.

2. A drawing machine feeder comprising

- a plurality of grooved feeding rollers extending transversely of said feeder, a plurality of tilttable pressure devices rotatively applied at intervals to each roller and supports 5 for said devices to position the same above said rollers, said supports presenting an outwardly directed edge to form conveying channels for the advancing material.
3. A drawing machine feeder comprising 10 a plurality of rollers having a series of parallel ribs thereon presenting angular edges, a plurality of separate pressure devices applied to said rollers at intervals and adapted to be rotated by contact and a plurality of 15 supports for said pressure devices for tiltably positioning the same above said rollers, the outward portion of said support defining edges forming conveying channels for feeding separate lines of cardable material between said pressure devices and said rollers.
4. A feeder for a drawing machine comprising a feed roller extending across the line 20
- of travel of the material and a plurality of separate pressure devices spaced apart and cooperating with said roller to feed in unison 25 separate lines of sliver to the machine.
5. A feeder for a drawing machine comprising a plurality of horizontally spaced rollers, a plurality of pressure devices spaced apart cooperating with each spaced roller 30 and adapted to feed in unison separate lines of sliver to the machine.
6. A feeder for a drawing machine comprising a plurality of horizontally spaced rollers, extending transversely across the line 35 of travel of the material, a shaft parallel to said rollers and extending across the feeder, yokes mounted on said shaft and a plurality of pressure devices spaced apart, cooperating with each spaced roller and 40 adapted to feed in unison separate lines of sliver to the machine.

AUGUST J. RICK.
JOHN FLIEDNER.
